(57) **CLAIM**

The ornamental design for a circuit interrupter cover, as shown and described.

DESCRIPTION

FIG. 1 is a front perspective view of the circuit interrupter cover;

FIG. 2 is another front perspective view of the circuit interrupter cover;

FIG. 3 is a front elevational view of the circuit interrupter cover;

FIG. 4 is a left side elevational view of the circuit interrupter cover;

FIG. 5 is a right side elevational view of the circuit interrupter cover;

FIG. 6 is a top plan view of the circuit interrupter cover;

FIG. 7 a bottom plan view of the circuit interrupter cover; and,

FIG. 8 is a rear elevational view of the circuit interrupter cover.

1 Claim, 6 Drawing Sheets
